UNITED STATES PATENT OFFICE.

PARKER RICHARDSON BRADLEY, OF EAST ORANGE, NEW JERSEY, ASSIGNOR TO AIRCRAFT FIREPROOFING CORPORATION, OF NUTLEY, NEW JERSEY, A CORPORATION OF NEW JERSEY.

METHOD OF DOPING AIRCRAFT.

1,309,454.

Specification of Letters Patent.

Patented July 8, 1919.

Application filed December 22, 1917. Serial No. 203,443.

To all whom it may concern:

Be it known that I, PARKER R. BRADLEY, a citizen of the United States, and a resident of East Orange, in the county of Essex and State of New Jersey, have invented a new and Improved Method of Doping Aircraft, of which the following is a full, clear, and exact description.

This invention relates to an improved method of applying dope or fireproof coating liquid to wing and other surfaces of flying machines, and the invention has for its general objects to improve the system of carrying on this work so as to be economical, expeditious, eliminate waste and at the same time prevent danger of poisoning the employees from noxious fumes or creating a nuisance to the neighborhood in which the plant is established.

While an aeroplane is very large and bulky, measuring forty to seventy feet and more from tip to tip of wings, it is made up of a number of comparatively small sections jointed one to the other with metal attachments. These sections are constructed of small pieces of wood as a framework over which is stretched linen or other cloth. Owing to the shape of the frame it is not possible to stretch the cloth on tightly, therefore a "dope" or waterproof coating is used, which as it dries will contract and draw up the linen cloth to a tight, drumlike surface. It is customary to apply a number of coatings of dope, say six to ten coats, and when all are dry to apply one or more coatings of spar varnish, which stands the weather better than any dope.

Heretofore all this work has been done by hand, employing skilled painters, and each coating is dried in the workroom, and takes five or more hours, depending on the weather. During the drying, poisonous gases or vapors are given off in great volume, which, if a large business is done, invariably causes sickness among the employees, and sometimes results in the death of employees, besides being an offense to the entire neighborhood; and the aeroplane takes about ten days for its completion.

The present methods when followed on a large scale have several serious objections, such as poisoning the employees; creating a nuisance in the neighborhood; labor

troubles owing to these two; endless delays, and eight to ten days to completely dope an 55 aeroplane, dependent on the weather; immense amount of factory space required for this hand work, and a waste of costly solvent which now poisons the help and neighbors, instead of being recovered and used 60 over again.

The improved method consists briefly in arranging the hollow sections of the wings of the aeroplane to be dipped on suitable dipping frames, submerging the frames and 65 aeroplane parts in a tank containing a dope which is sufficiently liquid to permit of dipping, raising the frames and dipped parts out of the tank, and then conducting them through an air-tight drying chamber which 70 has suitable means for drawing off and condensing the vapor and fumes. Before the sections of the wing are dipped each is provided with a drain opening at the bottom so as to permit the surplus dope to drain 75 off the inner surface of the fabric.

For a more complete understanding of the invention reference is to be had to the following description and claims taken in connection with the accompanying drawings, 80 in which similar characters of reference indicate corresponding parts in all the views, and in which

Figure 1 is a plan view of one of the cars on which the dipped parts hang during the 85 dipping and drying operation;

Fig. 2 is a vertical section showing a plurality of wing sections suspended on a car and submerged in a deep tank.

The carriage B on which the wing sections 90 are supported while being dipped or while drying, travels on rails 7 from the dipping station to the drying room, and from the latter to a point of discharge. In the dipping room are track rails 12 on which is a 95 tank 13 into which the wing sections are dipped.

The car B comprises a horizontal car frame 15 having trolley wheels 16 by which the car is suspended on the track rails. On 100 the car frame is an elevating frame 16* embodying corner uprights 17 which have rack teeth 18. These teeth mesh with pinions 19 on horizontal cross shafts 20, which latter are connected by gears 21 with a longitudinal shaft 22. On the shaft 22 is a 105

large gear wheel 23 which meshes with a pinion 24 on a transverse operating shaft 25 that carries a brake wheel 26 with which engages a brake band or equivalent means 27 which normally is frictionally engaged with the brake wheel so that the elevating frame 16^a will be held raised. On the end of the shaft 25 is a clutch element 28 which is adapted to engage with a clutch element 29 on a power shaft 30 located in the tank-room 2. The shaft 30 is moved longitudinally to engage or disengage the clutch elements 28 and 29 when a car B is in proper position over the dipping tank. When so positioned the brake band is slightly released, so that the elevating frame can be lowered to submerge the parts to be coated in the tank, and after the lapse of a proper period of time the power may be applied to the shaft, either by hand or motor, to gradually raise the elevating frame and remove the coated parts from the tank. When the elevating frame 16^a is fully raised the brake device is set and the clutch element 29 disengaged from the clutch element 28, so that the car with the coated parts thereon can be moved into the oven. Dipping frames 31 are employed to support the aeroplane wing sections and the other parts that are to be coated, these frames being attached by suitable connecting devices 32 to the elevating frame 16. The means for attaching the aeroplane parts to the dipping frames are not shown, as any suitable devices may be employed.

The operation is as follows:

The dipping frame loaded with aeroplane parts is placed in dipping room over the tank containing the dope. The power is started and the dipping frame lowers the aeroplane parts into the tank at the greatest speed possible without splashing and they remain a few moments; they are then raised very slowly indeed, completely out of tank and allowed to drain a few moments. The total time consumed in applying one coat to an aeroplane should be about fifteen minutes, divided as follows: one minute to enter; three minutes to soak; six minutes to withdraw; five minutes to drain. The door to the drying room is then opened and the car with the dipping frame and contents enters oven and the door is closed. It may take a longer or a shorter period of time. The lowest parts of the aeroplane sections are to have drain holes bored through the wood frames, with metal sockets; aluminum is the lightest weight for sockets. These sockets prevent the weakening of the frame. The first coat of dope soaks through, coating the back of the fabric as much as the face and thereby obtaining a far superior effect than is obtained by brushing on the dope by hand or any other way. Of course the dope inside the aeroplane frames must be

allowed to run out through the aforesaid holes. The drain holes allow the dope liquid to escape and drain the inside of the covered wing completely. After dipping the car is moved into drying oven and the vapors arising from the drying process are condensed into solvents. It requires about an hour to dry, this period will be more or less according to the boiling points of the solvents used and the heat of the drying ovens. With air locks and a partial vacuum in the drying ovens a solvent may be used of a very low boiling point, whereas when the work is done by hand, as is now the invariable custom, in the open air of the ordinary workshop, a large proportion of high boiling point solvent must be used to offset the dampness in the air. This is a very important point, as low boiling solvents are usually far cheaper than the high boiling solvents and are not of such an obnoxious odor and are not as poisonous.

When the surface of the cloth on wings is dope-tight, say after first or second dipping, the drain holes should be plugged with corks or plugs, as no further drainage is needed, as the dope will have ceased soaking through the cloth. After the desired number of coatings of dope have been applied, the dope tank is replaced with a tank of spar varnish and the door between the drying oven and dipping room is opened so the temperature of the dipping room is raised to around 90° Fahrenheit, more or less, and the doped frames are dipped into the spar varnish. The varnish and room must be warm and the dipping is done very slowly, taking at least twenty minutes and the ordinary commercial spar varnish may be thinned down with turpentine. After the coating of spar varnish has been applied the car is moved into the drying room and dried two hours and then moved into open air of workshop.

The solvents are condensed but are drawn off into separate barrels from those containing dope solvents. The varnish requires six hours to dry sufficiently so the wings may be removed from dipping frame and hung up in storage lofts.

Having thus described my invention, I claim as new and desire to secure by Letters Patent:

1. The method of doping a hollow aeroplane wing section having a fabric-covered frame with drain openings in the frame, which consists in dipping the said section in a coating material long enough to permit the coating material to penetrate through the pores of the fabric, draining the surplus material from the outer and inner surfaces of the wing section, drying the coating material, and repeating the dipping, draining and drying steps a plurality of times.

2. The method of doping a hollow aeroplane wing provided with drain means for

the chamber of the wing, which consists in supporting the wing in position with the drain means at the bottom and dipping the wing thus supported in a coating liquid, re-
5 moving the wing from the liquid, support-
ing the wing whereby the surplus liquid can drip off the outer surface of the wing and

drain out the drain means of the chamber, closing the drain means, and repeating the dipping and draining operation, whereby 10 only the outer surfaces of the wing will receive another coating.

PARKER RICHARDSON BRADLEY.
